JAMES F. WEST AND WILLIAM O. COWLEY, OF WICHITA, KANSAS.

MIXING-MACHINE.

No. 833,014.

Specification of Letters Patent.

Patented Oct. 9, 1906.

Application filed March 15, 1906. Serial No. 306,249.

To all whom it may concern:

Be it known that we, JAMES F. WEST and WILLIAM O. COWLEY, citizens of the United States, residing at Wichita, in the county of Sedgwick and State of Kansas, have invented certain new and useful Improvements in Mixing-Machines, of which the following is a specification.

Our invention relates to certain new and useful improvements in mixing-machines for concrete or the like; and the object of the invention is to provide a machine of this type which is composed of comparatively few and simple parts that will be durable in construction and which may be run easily and effectively to thoroughly mix the required ingredients, first in a dry state and then wet, if desired, and finally discharge them in a continuous stream at the outer end of the machine.

For a full description of the invention and the merits thereof and also to acquire a knowledge of the details of construction of the means for effecting the result reference is to be had to the following description and accompanying drawings, in which—

Figure 1 is a transverse sectional view of our improved mixing-machine. Fig. 2 is a side elevation thereof with parts broken away. Fig. 3 is an end elevation from one end of the machine. Fig. 4 is a similar view of the upper portion of the machine looking at the opposite side. Figs. 5 and 6 are detail views of one of the feeding-rolls.

Corresponding and like parts are referred to in the following description and indicated in all the views of the drawings by the same reference characters.

Our improved machine comprises a supporting-framework 1, which may be of any desired construction and which supports the hoppers 2 and the other parts of the machine. The hoppers 2 are provided with a common discharge-chute 3, and the passage of the ingredients to said chute from the discharge ends of the hoppers is controlled by means of corrugated rolls 4, preferably geared together and mounted on shafts 5. Underneath the discharge-chute 3 is located a sluice 6, which is inclined, as shown in Fig. 1, and is provided on its upper surface with a series of steps 7. The sluice 6 is mounted at its upper end upon a crank-shaft 8 and is pivotally held or supported at its lower end in hangers 9. Underneath the discharge end

of the sluice 6 is a horizontally and longitudinally extending mixing-drum 10, provided with a feed-opening directly underneath the discharge end of the sluice 6 and preferably provided at one side with a flange 11 to properly direct the materials from the sluice into the mixing-drum. Within the mixing-drum is journaled a longitudinally-extending shaft 12, provided with a series of mixing-shovels 13, that are oblique to the axis of the shaft, so that as the shaft is turned the ingredients will be conveyed gradually from the mixing-drum to the discharge end thereof while they are being mixed.

The mixing-shaft 12 may be driven by any suitable power—for instance, by means of a crank-handle 14—and said shaft is provided with a sprocket 15, connected by sprocket-chain 16 to a similar sprocket 17 on the crank-shaft 8. On the shaft 12 is another sprocket 18, connected by a chain 19 to a sprocket 20 on one of the shafts 5. The shafts 5 are geared together, preferably at opposite sides of the machine, as illustrated in Fig. 4, by means of spur-gears 21 and 22, one of which is preferably larger than the other and which are proportioned in size according to the ingredients desired to be fed from the hoppers. For instance, in the case of mixing concrete with our machine where one part of cement may be mixed with, say, five parts of sand the proper proportions of the ingredients are fed by proportioning the gear-wheels as shown in Fig. 4, in which case the roll or small gear will discharge five parts of sand or have five revolutions to one part of cement or one revolution of the other roll. It is to be understood, however, that our machine is not confined to the mixing of concrete only, but may be used for mixing purposes generally, and where certain proportions are to be accurately obtained and thoroughly mixed the wheels 21 and 22 will be changed in diameter accordingly, said wheels being preferably provided in pairs and properly proportioned to each other, according to the particular use intended.

As the ingredients are fed from the hoppers, the shaft 12 being actuated as above described, the ingredients will fall upon the sluice 6 at its upper end, and as said sluice is shaken or vibrated by means of the crank-shaft 8 the ingredients will be thoroughly mixed in a dry state before passing downwardly off the lower end of the sluice into the

mixing-drum 10. The ingredients are then preferably mixed wet, and for this purpose a pipe 23 is provided, said pipe extending across the machine, preferably at the feed or receiving end of the mixing-drum, and provided with suitable orifices for the proper distribution of the water at said points. The pipe 23 is preferably provided with a screw-threaded end 24 or is similarly formed for the convenient attachment of a hose or the like. As the ingredients are fed into the receiving end of the mixing-drum in their thoroughly dry-mixed condition the rotating shaft 12, with its shovels 13, will cause a thorough mixing of the materials in a wet condition and will at the same time gradually convey the mixed materials to and out of the discharge end of the machine, as indicated by the arrows in Fig. 2.

From the foregoing description, in connection with the accompanying drawings, it will be seen that we have provided a mixing-machine for concrete, mortar, or similar material which will first thoroughly effect a commingling of the ingredients by the vibrating sluice 6 and then will also effectively mix the materials after they have been sprayed by the action of the mixing devices in the mixing-drum 10 and finally discharge the same in their proper condition. It is to be noted that the machine is light in structure and yet durable in construction and that it may be easily operated. It is further to be noted that the ingredients fed from the hoppers may be variously proportioned by changing the diameters of the wheels 21 and 22, as before set forth.

Having thus described the invention, what is claimed as new is—

A mixing-machine of the character described comprising a supporting-framework, hoppers mounted thereon, corrugated rolls controlling the discharge ends of said hoppers, gearing arranged to operate said rolls simultaneously, an inclined vibratory sluice underneath said hoppers and arranged to receive the material discharged therefrom, said sluice being provided with a stepped bottom, a crank-shaft supporting the upper end of said sluice, hangers from which the lower end of said sluice is suspended, a mixing-drum having a feed-opening underneath the lower end of said sluice, a spray-pipe mounted in the framework, provided with jets designed to direct water or steam into the feed-opening of the mixing-drum and said pipe arranged for attachment to a supply-hose or the like, a mixing-shaft in said drum, conveying or mixing shovels mounted on said shaft, means for actuating said shaft, operative connections between said shaft and the crank-shaft, and other connections between said shaft and one of the shafts of said corrugated rolls, whereby the crank-shaft and rolls will be driven from the mixing-shaft, substantially as described.

In testimony whereof we affix our signatures in presence of two witnesses.

JAMES F. WEST. [L. S.]
WILLIAM O. COWLEY. [L. S.]
